(57) **CLAIM**

The ornamental design of a three wheel scooter, as shown and described.

DESCRIPTION

FIG. 1 is a front and top perspective view of the design of a three wheel scooter of the present invention. The seat portion mounted on the rear seat post, as illustrated in this FIG. 1, is shown in phantom whereby disclaimed and does not form a part of the present design.

FIG. 2 is a rear and top perspective view of the three wheel scooter shown in FIG. 1.

FIG. 3 is a front elevational view of the three wheel scooter shown in FIGS. 1 and 2.

FIG. 4 is a rear elevational view of the three wheel scooter shown in FIGS. 1-3.

FIG. 5 is a right side elevational view of the design of the three wheel scooter shown in FIGS. 1-4.

FIG. 6 is a left side elevational view of the three wheel scooter shown in FIGS. 1-5.

FIG. 7 is a top plan view of the three wheel scooter shown in FIGS. 1-6; and,

FIG. 8 is a bottom plan view of the three wheel scooter as shown in FIGS. 1-7.
